UNITED STATES PATENT OFFICE.

EDWARD LAVOIE, OF KANKAKEE, ILLINOIS.

CULTIVATOR.

1,091,358.

Specification of Letters Patent. Patented Mar. 24, 1914.

Application filed April 22, 1912. Serial No. 692,344.

To all whom it may concern:

Be it known that I, EDWARD LAVOIE, a citizen of the United States, residing at Kankakee, in the county of Kankakee and 5 State of Illinois, have invented certain new and useful Improvements in Cultivators, of which the following is a specification.

This invention relates to cultivators having pivoted axles which are controlled by 10 foot-levers.

It is the object of the present invention to provide an auxiliary hand-operated device for controlling the axles, and to this end the invention consists in a novel construction 15 and arrangement of parts to be hereinafter described and claimed.

In the accompanying drawing forming a part of this specification, Figure 1 is a front elevation of a cultivator, partly in section, 20 provided with the hand-operated controlling device. Fig. 2 is an enlarged sectional detail of the device.

Referring specifically to the drawing, 5 denotes the two supporting wheels of the 25 machine. The axle of each wheel is carried by a casting 6 having a vertical pivot connection with a bracket 7 carried by the main frame of the machine. To the casting 6 is connected a steering lever 8 provided with a 30 foot piece 9. The casting 6 is connected by an arm 10 to a transverse connecting bar 11, by means of which a simultaneous movement of the axles is produced. These parts, as well as the cultivator beams and other 35 details of the machine, are constructed and arranged in the ordinary manner, and nothing is claimed with respect thereto, in view of which, a further description of the same is deemed unnecessary.

40 The main frame of the machine carries a pair of laterally spaced, rearwardly extending seat-supporting bars 12, at the rear ends of which the driver's seat 13 is secured. Between the seat-bars, in front of the seat, 45 is rigidly bolted, or otherwise fastened, a bearing block 14 in which is journaled a

vertical steering shaft 15 having its upper end fitted with a steering wheel 16. On the bottom of the steering shaft is fastened, or formed integral therewith, a steering arm 17 50 which extends in diametrically opposite directions laterally from the shaft. The extremities of the arm are connected by links 18 to the lever 8, one of the links being connected to the lever of one of the axles and 55 the other link to the lever of the other axle. It will therefore be evident that the axles may be shifted about by operating the steering wheel 16, the rotary movement of the shaft 15 being transmitted by the arm 17 and 60 the links 18 to the lever 8. The wheels can also be swung around by the operator's foot in the usual manner.

By the hand-operated steering device herein described, the machine can be easily 65 steered without the operator using his feet. The device is extremely simple and can be readily applied to any cultivator of the type herein shown and described, no alteration or modification in the structure thereof being 70 required.

I claim:

An attachment for pivoted axle cultivators comprising a bearing provided with openings adapted to receive attaching bolts, 75 a steering post journaled in said bearing and provided with a thrust collar to prevent movement of the post through the bearing in one direction, a steering arm fixed upon the lower end of said post and constituting 80 a stop to prevent upward movement of the post, and links pivoted to the ends of the steering arm and adapted for connection to the projecting steering levers of a cultivator.

85 In testimony whereof I affix my signature in presence of two witnesses.

EDWARD LAVOIE.
